UNITED STATES PATENT OFFICE.

STERLING C. LINES, OF LOS ANGELES, CALIFORNIA, ASSIGNOR TO THE F. BISSELL COMPANY, OF TOLEDO, OHIO, A CORPORATION OF OHIO.

VACUUM CLEANER

Original application filed April 17, 1922, Serial No. 553,442. Divided and this application filed October 29, 1923. Serial No. 671,325.

To all whom it may concern:

Be it known that I, STERLING C. LINES, a citizen of the United States, and a resident of Los Angeles, in the county of Los Angeles and State of California, have invented a new and useful Vacuum Cleaner, which invention is fully set forth in the following specification.

This invention relates to vacuum cleaners and has for its object the provision, in combination with a portable vacuum cleaner, of a suction nozzle which is carried by the machine frame for vertical adjustment relative thereto to permit a varying space between its mouth and a subjacent surface, without requiring a tilting of the machine for such purpose, as is customarily done, and the provision of simple means for adjustably clamping the nozzle of the machine frame. This invention permits an adjustment of the nozzle with respect to the surface over which it is operated without disturbing the parallel relation of the nozzle mouth or inlet end with respect to such surface or the horizontal axis of the frame with respect to such surface.

The invention is fully described in the following specification, and while, in its broader aspect, it is capable of embodiment in numerous forms, a preferred embodiment thereof is illustrated in the accompanying drawings, in which—

Figure 1 is a front elevation of a cleaner embodying the invention, with the dust collecting bag removed and with the handle broken away. Fig. 2 is a side elevation thereof. Fig. 3 is a fragmentary front view of the adjustable nozzle clamping means, and Fig. 4 is a section thereof on the line 4-4 in Fig. 3.

This application is filed as a division of applicant's co-pending application Serial No. 553,442 filed April 17, 1922.

Referring to the drawings, 1 designates the cleaner frame or housing, in the present instance, of a cylindrical form with its axis horizontally and longitudinally disposed and having at its front end a fan casing 2, as is customary in a number of cleaners of this class. The frame or housing is supported preferably beneath or at the sides of the fan casing 2 by a pair of small wheels or rollers 3 mounted on suitable spindles at each side of the casing axis and the frame is

supported at its rear by a single caster 55 wheel 4 which is mounted for horizontal swinging movements. 5 designates the handle of the cleaner which is provided with a fork 6 at its lower end which straddles the frame 1 and is in pivotal connection 60 therewith.

The fan casing 2 has its front or outer side flat and provided centrally with the customary air inlet opening 7. The suction nozzle 8, which is of customary form, has its neck terminating at its inner end or at the end thereof opposed to the nozzle mouth with a surrounding laterally projecting flange 9 of flat form and of a size to adapt it to seat flat against the front side of the fan casing 2 in surrounding relation to the inlet opening thereof. The fan casing is provided on its front side at opposite sides of its opening with vertically disposed guide strips 10 between which the side edges of the nozzle flange 9 are adapted to fit, being guided thereby for vertical adjustment so that the nozzle may be raised or lowered with respect to the machine frame and also the surface over which the machine is operated, without disturbing the parallel relation of the inlet end of the mouth piece to such surface.

The nozzle 8 is clamped in adjusted relation to the fan casing by clamping fingers 85 11 which, in the present instance, are of a spring nature, and project from the outer edges of the guide strips 10 across the outer sides of such strips with their free ends in overhanging or clamping relation to the flange 9. The guide strips 10 and fingers 11 are connected by screws or bolts 12, which are provided in the present instance, with wing nuts 13 operable to effect a clamping of the fingers against the flange 9 to hold 95 the same firmly to the fan casing.

This manner of releasably and adjustably carrying the nozzle by the fan casing is important as it not only enables the nozzle to be easily and quickly removed from the machine or engaged therewith, as the case requires, but also enables it to be easily and quickly raised or lowered with respect to the machine frame as it may be desired to increase or diminish the space between the inlet end or mouth of the nozzle and the surface over which it is operating, without any angular adjustment of the nozzle or of

the longitudinal axis of the frame 1 with respect to such surface as would be the case where such adjustment is obtained by a tilting of the machine frame. In other words, 5 the machine frame at all times is permitted to remain with its axis parallel to the surface over which operating, and the adjustment of the nozzle is always at right angles to such surface and axis of the machine so 10 that an adjustment of the nozzle does not dispose one edge of its mouth a greater distance from the floor or other subjacent surface than the other edge.

I wish it understood that the invention 15 is not limited to any specific construction, arrangement or form of the parts, as it is capable of numerous modifications and changes without departing from the spirit of the claims.

20 What I claim as new and desire to secure by Letters Patent, is,—

1. In a vacuum cleaner, a frame having a fan casing at one end with the outer side of the casing provided with an inlet opening, a nozzle having a laterally projecting neck flange for seating against the casing in surrounding relation to its opening and for adjustment transversely of the opening, and means engaging the neck flange for readily securing the nozzle in adjusted relation to the casing.

2. In a vacuum cleaner, a frame having

a fan casing at one end with the outer side of the casing substantially flat and provided with an inlet opening, vertical guides fixed 35 to the outer side of the casing at opposite sides of the opening, a nozzle adapted to seat at its inner end against the casing side in enclosing relation to its opening and having lateral projections for guiding coaction with the guides to permit vertical adjustment of the nozzle relative to the casing opening, and means operable to coact with the nozzle projections to secure the nozzle in adjusted position. 40 45

3. In a vacuum cleaner, a motor housing having a fan casing at one end with the outer side of the fan casing substantially flat and provided with an inlet opening, vertical guide members secured to the outer 50 side of the casing at opposite sides of its opening, a nozzle having a flange at its inner end for seating flat against the casing side in surrounding relation to its opening and between the guide members in vertically 55 sliding engagement therewith, spring clamping fingers carried by the casing, and means operable to cause the fingers to have clamping engagement with the nozzle flange to hold the nozzle in adjusted relation to 60 the casing.

In testimony whereof I have hereunto signed my name to this specification.

STERLING C. LINES.
